UNITED STATES PATENT OFFICE.

FRANK M. JOSLIN, OF AMSTERDAM, NEW YORK, ASSIGNOR TO INMAN MANUFACTURING COMPANY, INC., OF AMSTERDAM, NEW YORK, A CORPORATION OF NEW YORK.

COLLAPSIBLE CORE FOR PAPER-ROLLS.

1,317,166.

Specification of Letters Patent. Patented Sept. 30, 1919.

Application filed January 26, 1918. Serial No. 213,948.

To all whom it may concern:

Be it known that I, FRANK M. JOSLIN, a citizen of the United States, and residing at Amsterdam, Montgomery county, State of New York, have invented certain new and useful Improvements in Collapsible Cores for Paper-Rolls, of which the following is a specification.

This invention relates to collapsible cores for supporting rolls of paper or cloth fabric and particularly to cores for paper rolls, which are generally large and heavy and which must be shipped long distances from the factories to the consumers and back to the factory, when it is desired to use them more than once.

The object of the invention is to provide such a core which is of substantial construction, enabling it to be used repeatedly and which is collapsible, thus permitting it to be taken apart when the roll has been unwound therefrom, and packed for shipment back to the factory in much less space than it would have otherwise required.

The invention will be fully revealed in the following description taken in connection with the accompanying drawings, in which:

Figure 1 is a side elevation of the collapsible core, portions being broken away to disclose the details of construction;

Fig. 2 is a section along the line 2—2 of Fig. 1;

Fig. 3 is a plan view of a portion of a disk and bar illustrating the manner in which they are placed together;

Fig. 4 is a section along the line 4—4 of Fig. 2.

The invention comprises essentially two metal disks preferably of cast iron, a plurality of wooden bars adapted to connect said disks, and a plurality of blocks coöperating with the bars and disks and locking them into a rigid structure upon which a strip of fabric may be wound, but which are removable at will, thereby allowing the disks and bars to be separated and packed for shipment in a reduced space.

More particularly the core comprises two cast iron disks or heads 10 each having a series of marginal rectangular openings 11 arranged around the periphery thereof, portions 12 of the disk projecting inwardly at each opening and constituting shoulders which coöperate with the block members 13 in holding the ends of the wooden bars 14

firmly within the openings 11. The wooden bars are rectangular in cross section, being substantially square in the present embodiment of the invention and of a size to fit the openings, the ends being slotted for a considerable distance, as shown in Figs. 1 and 3 of the drawings. The wood is flexible and the side portions of the bars may be pinched together as shown in Fig. 3 in order that the bars may be inserted radially within the openings 11, the outer ends of which are narrowed by the inwardly extending projections or shoulders 12.

When the ends of the bars have thus been inserted within corresponding openings 11 in the two disks the bevel edged block members 13, which are of substantially the same width as the slots in the ends of the bars, are inserted into these slots between the walls of the openings 11, thus holding the sides 75 of the bars against the sides of openings 11 and thereby preventing radial movement of the bars relatively to the disks since the shoulders 12 will engage the upper faces of the side portions of the bar to lock them 80 within the openings. In order to prevent the bars from slipping longitudinally relatively to the disks each of them is notched on the upper face at 15 as clearly shown in Fig. 4, and the shoulders 16 of these notches 85 engaging the opposite ends of projections 12 when the bars have been inserted, thus preventing such longitudinal movement.

The blocks 13 are inserted radially and are held within the slots by frictional engagement with the side portions of the bars, and also by the roll of fabric which is wound upon the core. These blocks 13 may be easily removed when the fabric has been unwound from the core by forcing them longitudinally from the ends of the slots, and when they have thus been removed the bars may be separated from the disks by pinching their ends together and lifting them from the openings 11 in exactly the reverse manner of their insertion thereinto, as shown in Fig. 3. The disks are provided with squared central openings 17 through which a suitable bar or shaft of a winding machine, printing press, paper box making machine, or other such machine may be passed to support the core when the fabric is being wound thereon or removed therefrom.

The disks 10 are flat metallic members having lateral flanges to provide increased 110

bearing areas for the wooden bars and for the shafts which may pass through the central opening 17. This construction allows the disks to be comparatively light in weight 5 and yet provide such necessary bearing surfaces.

From the foregoing description the operation of the invention is apparent. The bars and disks are put together and locked into 10 a rigid structure at the factory or point at which the strip of fabric is to be wound thereon. The core is then placed upon a winding machine and the proper length of fabric wound thereon, after which it is ready 15 to be shipped. When the material has been unwound from the core at the point of consumption the blocks 13 are removed from the slots in the ends of the bars and the bars removed from the openings in the disks, the 20 core being in this manner collapsed and the individual bars and disks being packed for shipment to the factory in a small space in comparison to that occupied by the core when erected.

25 Besides effecting a considerable saving in freight charges by thus reducing the space required for return shipment, the cores, because of the iron centers used prevent losses of paper or other fabric wound thereon, due 30 to the fact that the iron centered cores will run accurately in an automatic machine, such as an automatic paper box making machine, whereas the supporting disks of the usual wooden centered core become bruised 35 and flattened out in use so that they do not run accurately when placed on such a machine, and a considerable amount of paper on the outside of the roll will run badly into the machine, thus causing more or less waste 40 of stock.

Having thus described the invention what is claimed as new and desired to be claimed by Letters Patent is:

1. A collapsible core for rolls of fabric including in combination a plurality of disks adapted to be arranged in parallel relation each disk having a series of openings therein arranged in a circle, a plurality of bars each of which is adapted to pass through 45 corresponding openings in each disk, and means insertible into each opening through its mouth to hold the bar therein immovable relatively to the disk, said means being also removable at will, whereby the disks and bars may be formed into a rigid core to support a roll of fabric, or separated for shipment, as desired.

2. A collapsible core for rolls of fabric, including in combination two disks adapted 60 to be arranged in parallel relation each having a series of marginal slots, a plurality of bars each of which is adapted to pass through corresponding slots in each disk, and means insertible into each slot through 65 its mouth to hold the bar therein immovable

70 relatively to the disk, said means being also removable at will, whereby the disks and bars may be formed into a rigid core to support a roll of fabric, or separated for shipment, as desired.

3. A collapsible core for rolls of fabric, including in combination a plurality of disks adapted to be arranged in parallel relation each disk having a series of openings therein arranged in a circle, a plurality of bars 75 each of which is adapted to pass through corresponding openings in each disk, each bar having a slot therein at the point where it engages a disk, and means insertible into each of said slots to hold the bar immovable 80 relatively to the disk, said means being also removable at will whereby the disks and bars may be formed into a rigid core to support a roll of fabric, or separated for shipment, as desired.

85 4. A collapsible core for rolls of fabric, including in combination a plurality of disks adapted to be arranged in parallel relation each disk having a series of peripheral openings with inturned portions projecting into said openings, a plurality of bars adapted to pass through and closely fit corresponding openings in each disk, each bar being slotted longitudinally so that its 90 sides may be pinched together and the bar inserted beneath said projecting portions, and means insertible within said longitudinal slots adjacent each disk to hold the side portions of said bars beneath said inturned 95 portions to be held thereby, said means being removable at will, whereby the disks and bars may be formed into a rigid core to support a roll of fabric, or separated for shipment 100 as desired.

5. A collapsible core for rolls of fabric, 105 including in combination a plurality of disk members adapted to be arranged in parallel relation each disk member having a series of peripheral openings therein, a plurality of bar members adapted to pass through and closely fit corresponding openings in each disk, and means for locking said bar members within said openings, said means comprising projections on one of said members adapted to engage the other member and elements insertible within said openings and removable at will, whereby the disks and bars may be formed into a rigid core structure to support a roll of fabric or separated 110 for shipment, as desired.

115 6. A collapsible core for rolls of fabric, including in combination two disk members adapted to be arranged in parallel relation each having a series of radial rectangular marginal openings therein with overhanging 120 projecting shoulders, a plurality of rectangular bars adapted to pass through the corresponding openings of each disk each bar having its ends slotted longitudinally thereof so that the side portions may be 125 130

pinched together in inserting the same into the openings to clear the projecting shoulders, and blocks insertible within said slots to hold the side portions of the bars against the sides of the slots to be locked therein by said shoulders, said blocks being removable

at will whereby the disks and bars may be formed into a rigid core to support a roll of fabric, or separated for shipment, as desired.

10

In testimony whereof I affix my signature.
FRANK M. JOSLIN.
